CLAIM

An ornamental design for a kiosk section, as shown and described herein.

DESCRIPTION

FIG. 1 is a perspective view of a kiosk section of our new design.

FIG. 2 is right side view of the kiosk section of FIG. 1.

FIG. 3 is left side view of the kiosk section of FIG. 1.

FIG. 4 is a front view of the kiosk section of FIG. 1.

FIG. 5 is a rear view of the kiosk section of FIG. 1.

FIG. 6 is a top view of the kiosk section of FIG. 1; and,

FIG. 7 is a bottom view of the kiosk section of FIG. 1.

Those portions shown in phantom do not form part of the design.

1 Claim, 6 Drawing Sheets
